INTERLOCKING JEWELRY ORNAMENT

Maurice A. Mayer, West Los Angeles, Calif.

Application May 18, 1935, Serial No. 22,159

4 Claims. (Cl. 63—15)

My present invention relates to the jewelry art, and has particular reference to the construction of rings, bracelets and the like.

Rings, bracelets, and similar ornamental jewelry has heretofore been designed to possess a distinctive ornamental appearance created in the mind of the designer, whereby the completed article as sold has an appearance and a visual effect that cannot be altered or changed by the owner. It has thus become necessary to have many different designs, colors, and arrangements, to permit a choice and a selection of jewelry most suitable for use with a particular dress or ensemble. It is the principal object of my invention to devise a jewelry construction that permits a wide latitude in changing effects to suit the appearance and mood of the user.

It is a further object of my invention to provide a construction that permits selective change in the size of the ornament as well as the color effect thereof.

An additional object of my invention is to provide a novel jewelry ornamentation suitable for jeweled and for metal effects, and for any selected combination thereof.

With the above and other objects and advantageous features in view, my invention consists of a novel arrangement of parts more fully disclosed in the detailed description following, in conjunction with the accompanying drawing, and more specifically defined in the claims appended thereto.

In the drawing,

Fig. 1 is a perspective view of the novel invention, as exemplified in a finger ring;

Fig. 2 is a side view of one ring base;

Fig. 3 is an enlarged section on the line 3—3 of Fig. 2;

Fig. 4 is a plan view thereof;

Fig. 5 is a side view of one intermediate ring element;

Fig. 6 is an enlarged section on the line 6—6 of Fig. 5;

Fig. 7 is a plan view thereof;

Fig. 8 is an elevation of a modified ring construction; and

Fig. 9 is an elevation of another modified ring construction.

Referring to the drawing, wherein like reference characters designate similar parts, the novel ring arrangement 10 includes two similar ring bases 11, 12 and a plurality of intermediate ring elements 13, the bases and elements being separable and free from each other, but having com-

plementary contours facilitating nesting engagement when positioned on a finger.

Thus, referring to Fig. 2, the illustrated bases each preferably have a plane edge 14, and an irregular edge 15 consisting of a plurality of angularly related surfaces 16 forming alternate projections 17 and depressions 18. The intermediate elements, see Fig. 5, each have two edges 19, 20 of complementary contour, each formed of angularly disposed surfaces 21 forming alternate 10 projections 22 and depressions 23, the depressions and projections of one edge being aligned with the projections and depressions of the other edge. The edges of the bases and the intermediate elements are preferably perpendicular to their peripheral surface, and their surfaces have complementary contours, whereby any selected number of intermediate elements may be nested between the two bases to form an assembled composite ring.

The bases preferably have recesses 24 to receive stones 25, and the intermediate elements are grooved as at 26 to receive stones 27, whereby the assembled ring presents an attractive appearance. The stones for the individual elements 25 may be of different collective or individual colors, whereby selected designs may be readily obtained by changing the intermediate elements, their relative positions, and their number, although stone-set elements are preferred, the intermediate 30 elements may be plain or ornamented, and of any material and any color, whereby a very large number of individually selected arrangements are possible. Moreover, the contiguous edges of the bases and of the intermediate elements 35 may be cut to form interlocking parts of the tongue and groove type, to increase the joining effect.

Although the preferred arrangement utilizes edges with angularly disposed surfaces, resulting 40 in a saw-tooth edge effect, any other complementary contours may be used, capable of obtaining the desired interlocking engagement. Thus, see Fig. 8, the bases 28, 29 and the intermediate elements 30 have wavy edges, as illustrated; and, see Fig. 9, the bases 31, 32 and the intermediate elements 33 have rack-teeth edges, as illustrated.

The interlocking relation may obviously be applied to jewelry items other than rings, such as 50 bracelets and the like, and may also be used for brooches, pendants, clusters, earrings, and similar articles. The fingers, wrist and forearms serve as supports for the ring and bracelet parts, which preferably are completely independent; other 55

articles may be provided with a suitable frame which permits ready mounting, removal, and replacement of the intermediate elements and the end bases. Although the illustrated intermediate elements are of uniform cross section, constructions may, if desired, be utilized having non-uniform cross section, to obtain unusual visual effects.

10 Although specific bases and intermediate elements have been described and illustrated, it is obvious that the shapes and widths of the bases, the widths of the intermediate elements, and their materials, thickness, and ornamentation, may be changed to suit any design requirements 15 for selective jewelry effects, without departing from the spirit and the scope of the invention as defined in the appended claims.

I claim:

1. A jewelry ornament comprising a pair of 20 end bases having outer edges approximately in planes extending transversely of the ornament and having the inner edges formed of regular alternate depressions and projections, and one or more intermediate elements having opposite 25 edges formed of regular alternate depressions and projections interfitting with the inner edges of the end bases.

2. A jewelry ornament comprising a pair of circular end bases having outer edges approximately in vertical planes extending transversely of the ornament and each having the inner edge formed of regular alternate depressions and projections extending in series relation circumferentially thereof, and one or more intermediate elements having opposite edges formed of regular alternate depressions and projections interfitting with the inner edges of the end bases.

3. A jewelry ornament comprising a pair of circular end bases, having outer edges approximately in vertical planes extending transversely of the ornament at right angles to the axis thereof, said bases having the inner facing edges there- 15 of formed of regular reentrant angles, and one or more intermediate elements having opposite edges formed of regular reentrant angles interfitting with the inner edges of the bases.

4. A jewelry ornament comprising a pair of 20 end bases having outer edges approximately in planes extending transversely of the ornament, and one or more intermediate elements between the end bases, said end bases and intermediate elements having alternate interfitting depressions 25 and projections.

MAURICE A. MAYER.
